UNITED STATES PATENT OFFICE.

MYRON H. KINSLEY, OF WALLINGFORD, CONNECTICUT.

DESIGN FOR A SPOON OR FORK HANDLE.

SPECIFICATION forming part of Design No. 12,428, dated August 23, 1881.

Application filed June 29, 1881. Term of patent 7 years.

To all whom it may concern:

Be it known that I, MYRON H. KINSLEY, of Wallingford, in the county of New Haven and State of Connecticut, have invented a new 5 Design for Spoon and Fork Handles; and I do hereby declare that the following, when taken in connection with the accompanying drawings and the letters of reference marked thereon, to be a full, clear, and exact description of the 10 same, and which said drawings constitute part of this specification, and represent a face view.

This invention relates to a design for spoons, forks, and like articles of table-service; and it consists in the ornamentation of the surface 15 of the handle, as shown in the accompanying illustration, and more fully hereinafter described.

The principal feature of this design is the representation of Niagara Falls and Suspension Bridge on the surface of the handle. The 20 falls are seen beneath the bridge, the rapids below the falls extending down upon the surface of the handle, with the representation of

the bank of the river upon each side, a diagonal ornamental band cutting off the river and 25 bank at the front. The diagonal band or ornamental termination or cutting off the foreground may be changed without departing from the design, the essential feature of which, as before stated, is the representation of Suspension 30 Bridge and Niagara Falls as seen in the distance, with a band across the face of the handle, back of which the rapids appear to pass, or which appears to cut off the river.

I claim—

The design for spoon and fork handle, consisting in the representation of Suspension Bridge and Niagara Falls on the surface of the handle, an ornamental band below cutting off the river, as shown in the accompanying 40 illustration.
